UNITED STATES PATENT OFFICE.

ALFRED M. REMINGTON, OF FITCHBURG, MASSACHUSETTS, ASSIGNOR, BY MESNE ASSIGNMENTS, TO SIMONDS SAW AND STEEL COMPANY, OF FITCHBURG, MASSACHUSETTS, A CORPORATION OF MASSACHUSETTS.

GROOVER SAW.

Application filed September 19, 1922. Serial No. 589,184.

To all whom it may concern:

Be it known that I, ALFRED M. REMINGTON, a citizen of the United States of America, and resident of Fitchburg, in the county of Worcester and State of Massachusetts, have invented new and useful Improvements in Groover Saws, of which the following is a specification.

This invention relates to the wood working art and in particular to a type of tool for producing grooves in wood commonly called groover saws.

Objects of the invention are to provide devices of the class described each of which shall be adapted to cut a groove of a certain fixed width, which shall require adjustment only for the depth of the groove, which produces grooves having clean cut sides regardless of the direction in which the grain runs and without splintering or chipping the wood, which may be easily sharpened, and in general to improve such devices to the end that they may be efficient and satisfactory in service.

For the purpose of illustrating the invention one concrete embodiment thereof is shown in the accompanying drawing in which:

Fig. 1 is a plan view;

Fig. 2 is an elevational view;

Fig. 3 is a section on the line 3—3 of Fig. 1;

Fig. 4 is a sectional view of a piece of wood as initially cut by the markers; and

Fig. 5 is a view similar to Fig. 4 showing the completed groove.

The embodiment of the invention shown for the purpose of illustration comprises a blade A circular in form and provided with markers 6 and rakers 7 on the periphery thereof. Markers 6 extend slightly beyond rakers 7 (Fig. 1) and serve to mark or cut the wood at each side of the groove to be made. Markers 6 are preferably in pairs, these pairs being disposed in alternation with rakers 7, the latter serving to remove the material between the cuts or marks made by markers 6.

The pairs of markers 6 are cut away on opposite sides as indicated in Fig. 2, at first rather sharply at 8, then more gradually for a considerable distance as indicated at 9, and then again sharply at 10, so that the cutting edges formed by the last bevel at 10 lie in

the planes of the parallel faces of the blade 55 A. The cutting edges of markers 6, which as shown in Fig. 1 are concentric with the axis of plate A, are serrated as indicated in Figs. 1 and 2 forming teeth 11. For ease in filing teeth 11 the cut away faces of markers 60 6 may be provided with parallel grooves 12, (Figs. 1 and 2). These grooves 12 are preferably extended the entire length of the markers 6 to form elongate coplaner ridges which gouge out or rasp away the wood 65 initially cut by teeth 11 and thus prevent binding of markers 6 in the wood as the latter is being worked on.

Rakers 7 are made with a substantial hook end or forwardly inclined surface 13, providing a cutting edge 14 extending transversely of blade A and which acts as a chisel in cutting out the material between the marks made by markers 6 to form the groove in the wood. From the cutting edge 14, 70 each raker 7 preferably tapers rearwardly at 15 (Fig. 1) to afford clearance. The rakers are preferably narrower than the groove to prevent chipping the edges of the groove and the rakers may be slightly beveled at the sides as indicated at 16 in Fig. 2.

In operation the saw is mounted for rotation in the usual saw table and the stock is forced over the projecting sector of the saw. Since the markers 6 project beyond the 85 rakers 7, the former first engage the stock producing shallow parallel cuts b as indicated in Fig. 4. As the stock B is advanced the cuts b which define the sides of the groove become deeper and the cutting teeth 90 or edges 14 of the rakers 7 begin to remove the material between the cuts b, the completed groove being shown in Fig. 5.

From the above it will be apparent that a saw constructed in accordance with the disclosure of this application is adapted to produce grooves having clean cut sides without splintering or otherwise defacing the material, that the saws may be made of any desired size and of thickness to correspond 100 to the width of the groove to be cut, and that the fashioning of the projections 6 forming the markers is such as to provide cutting teeth of great strength which will make a clean cut and not bind by reason of 105 the grooves 12 on the cut away faces of the teeth which rasp away the wood and also serve as guides in sharpening teeth 11, and

2
that the only adjustment necessary is for the depth of the groove.

I claim:

1. A groover saw comprising a blade having integral cutters disposed in the planes of the faces of the blade respectively to mark the outside dimensions of the groove to be made, said cutters tapering arcuately from the cutting edges thereof to the full width of the blade, the curving sides of said cutters being ridged transversely as respects the cutting edge to rasp away the wood during the marking operation, and means arranged alternately with said cutters along said blade to rake the material between the marks made by said cutters.
2. A groover saw comprising a circular blade, axially spaced radial cutters arranged in pairs on said blade to mark the width of the groove and cutters between the pairs having transverse cutting edges for removing the material between the marks produced by said first cutters, the pairs of cutters being diametrically oppositely disposed and the sides of the teeth of a pair and the ensuing cutter having parallel front faces.
3. A groover saw comprising a circular blade having pairs of circumferentially directed cutters spaced about said blade, said cutters being adapted to mark the width of the groove to be cut, and rakers interposed between said pairs of cutters, the pairs of cutters having parallel bounding front and rear faces and the raker associated with each pair having its bounding faces parallel with those of its cutters, to remove the material between the marks made by said cutters.

4. A rotary saw comprising a circular body portion having diametrically opposed extensions each providing a pair of teeth, the opposite sides of the teeth of a pair being formed with correspondingly outwardly curving grooves and ribs intermediate the grooves, the termini of the teeth at the ribs and grooves being outwardly beveled to provide cutting points corresponding in number and location to the ribs, the cutting points of the adjacent pair of teeth being disposed at opposite faces of the body portion and separated by the width of such portion.

5. A rotary saw comprising a body portion having integral diametrically opposed extensions each split to provide a pair of teeth, the opposite sides of the teeth of a pair being formed with correspondingly outwardly curving grooves providing intermediate ribs and the termini of the ribs and grooves being outwardly beveled to provide cutting points corresponding in number and location to the ribs of the main teeth, the cutting portions of the adjacent pair of teeth being disposed at opposite faces of the body portion and separated by the width of said body portion and raker teeth intermediate the pairs for clearing out the material therebetween, said raker teeth being outwardly tapered to a thickness less than the space between the cutting points and greater than the space between the ribs.

Signed by me at Fitchburg, Massachusetts, this 24th day of August, 1922.

ALFRED M. REMINGTON.
